UNITED STATES PATENT OFFICE

THOMAS E. MARKLEY, OF LOS ANGELES, CALIFORNIA

INSTRUMENTALITY OF FRAME CONSTRUCTION

Application filed January 6, 1930. Serial No. 418,818.

This invention relates to improvements in means and instrumentalities for making supports, frames and other constructions.

One of the objects of this invention is to 5 provide a simple, efficient and inexpensive means designed for selective as well as interchangeable use in different situations and at varying angular positions.

Another object thereof is to provide a series 10 of interchangeable tubular posts so shaped, arranged and designed that they may be used to build brackets, forms, display racks, and serve to give outline and body to innumerable things constructed from wood or metal, and 15 serving also to strengthen any given construction.

A further object of this invention is to provide a light, strong, portable and interchangeable construction unit shaped to serve 20 as a brace, gusset, stay or other supporting member in a structure consisting either of rigid or movable parts, or else of semi-rigid and movable parts.

Another object of this invention is to provide 25 a construction unit characterized by the feature of adaptability to various uses in the building or construction line and lending itself readily to angular positions and for removable exigencies.

A still further object of this invention is 30 to provide a small construction unit serviceable interchangeably as a truss, a girder, a column, a brace, or a knockdown support for supporting the weight of a superincumbent 35 or surmounted or attached part.

A further object of this invention is to provide 40 a fastener and construction unit designed to receive the terminals of stay rods or similar parts for the purpose of supporting varying parts or objects in angular 45 position, or for the purpose of movably mounting a part in angular position.

In carrying out the objects of this invention 45 it is designed to provide a tubular post or the like shaped to provide a series of slots so shaped that each slot provides an angular or diagonal notch which communicates with a base opening or hole. Rows of slots are 50 provided in circumferential order and in a longitudinally alining series, and stay rods

will have their terminals initially introduced into the diagonal parts of the slots to be ultimately lodged in the base openings thereof. The upper planes of the slots are spaced 55 the greater distance from similar slots of adjacent posts so that it allows the ends of a stay rod or brace bar or the like to be readily fitted into these slots, so that when the rod is pressed downwardly both ends at the same time, they will be wedged home in the holes 60 forming the bases of these slots and thus be frictionally held against displacement in these slots.

With the above and other objects in view my invention consists in the combination, arrangement and details of construction disclosed in the drawings and specification, and then more particularly pointed out in the appended claims.

In the drawings, wherein similar reference characters designate similar parts throughout the respective views,

Figure 1 shows four views, fragmentarily, of the same construction unit, but viewed at quarter turns apart, in side elevation,

Figure 2 is a cross section taken thru one of the construction units,

Figure 3 is a vertical sectional view of a bushing used in connection with the tubular post or construction unit,

Figure 4 is a side elevation of the bushing shown in Fig. 3,

Figure 5 is a front elevation, partly in section, of a window shade having a stretch thereof disposed in angular formation to serve as an awning,

Figure 6 is a fragmental detail view, showing a method of assembling certain construction units,

Figure 6a is a perspective fragmentary view showing the parts of Figure 6 just before assembly,

Figure 7 is an end elevation of parts shown in Fig. 5,

Figure 8 is a plan view of a blank from which a construction unit is to be made,

Figure 9 is a view showing the blank of Fig. 8 rolled into columnar form,

Figure 10 is a plan view of a bracket blank designed to be shaped to varying forms.

Figure 11 is a perspective view of a boxing employed by bending the blank shown in Figure 10.

Figure 12 is a perspective view of another bracket made from the blank shown in Figure 10.

Figure 13 is a perspective view of another and further bracket form made from a blank like that shown in Figure 8, and

Figure 14 is a fragmental detail view of a construction unit showing a modified wedge slot formed therein.

Referring to the drawing, which are merely illustrative of my invention I provide a tubular post, column or member made preferably of metal or rigid material. Each tubular post is a construction unit primarily designed for the purpose of sustaining some extraneous part of a construction. The tubular unit or post may broadly be designated 10 and will be formed with a longitudinally spaced apart series of circumferentially arranged holes 11, which holes will preferably be arranged in sets that align at diametrically opposite points as at 11 and 11m of Figure 2. Each hole is formed with an extension notch which slopes angularly or diagonally of the axis of the post so that its outer edge 12m may or will be disposed parallel with the axis of the tubular post. In Figure 1 it will be perceived that there are four longitudinal rows of slots, the inclinations of the notches alternating in direction of slope, the units of slots of the four rows being designated 12, 12a, 12' and 12b, as in Figure 1. In other words, the slots of the four rows are staggered, and their diagonal notches alternate in direction of slope. In order to unite other hollow posts to certain posts, it is proposed to snugly locate a bushing 13 in the open end of the post, or of each post, the bushing being internally threaded as at 14 so that a screw-threaded stem 22 of a mated post may be screwed home into the internally threaded bore 14 of the bushing to clamp one post onto the other in alignment. Thus in Figure 1 the bushing M has the internal threaded bore N and, this bushing fits into one post and has screwed thereinto a threaded part of a mated post in a manner readily understood.

It is also proposed to provide a knockdown frame or support as follows, by employing the interchangeable construction units or hollow posts 10. Referring to Figure 6 it will be readily seen that one post 10p has the internal bushing 13m encased therein, while another and similar bushing 13 is snugly encased in the other hollow post shown arranged parallel with the first mentioned post, both bushings being internally screw threaded so that a plug 29 also screw threaded throughout its length will be threaded in part into the bushing 13, and in part into the bushing 13m to act as a means of coupling both posts. The openings 15 in the bushing will receive the

threaded stem 32 which is a reduced terminal carried at each end by a rod, bar, or other stay member 31. This stay member will preferably be a hollow post having a bushing therein provided with the stem 32, so after this stem has projected thru openings 15 a jam nut 34 may be screwed upon the stem and clamp it against the post 10; 33 designates the threads on the stem 32. In this manner making use entirely of hollow construction units or posts 10 a frame-work can be made consisting of vertical posts and horizontal stays. Any height of tubing or columns may be provided by means of the tubular posts in the manner herein shown.

The fundamental idea underlying the use of the diagonal slots is to make them receive the ends of a rod, bar or the like to retain them in connected relation frictionally. Thus in Figure 9 the end of a stay rod F is shown in dotted lines; it is seen how easily the end thereof may be fitted and introduced into the uppermost ends of the diagonal slot 12b; then this end may be forced downwardly into the hollow interior of the post until it comes to rest in the base hole 11b of this slot, at which time a larger surface of the terminal of this rod is frictionally encased in the post than was true when this end was introduced into the upper ends of the diagonal slot. This allows a rod to be manipulated in a more compact space than would be true if the ends were designed to be introduced directly into holes of adjacent posts.

It is proposed to make the mountings, posts, columns or the like of sheet metal if desired. For this purpose use is made of metal or other blanks S as shown in Figure 8 where there will be stamped or punched out therein the longitudinally aligning rows of diagonal slots indicated as follows; the first row of diagonal slots with their base holes take an upward and rearward slope and are designated D; the second row is staggered with respect to the first and slope in a counter direction, being designated E; the third slope in staggered relation with reference to the second row, and are designated F', sloping the same as the second row, while the last row are designated G, sloping the same as the first row and staggered with respect to the third row. This order and disposition is found necessary for the reason that when this blank or sheet is rolled to provide the tube 10 or the tube shown in Figure 9 it is contemplated that the diagonal slots E have their base holes diametrically opposite to the diagonal slots G; while the slots D will have their base holes diametrically opposite to the diagonal slots F; while one set of slots will be in registration as to their base holes their angular stems will incline in opposing directions. By aligning the base holes of the rows of these slots it permits the rod or terminals of any stay member to be received into these holes, both at the same

time, for the opposing ends of the rod. It is possible to shape blanks provided with the holes and diagonal stems into various bracket and supporting members. Thus in Figure 5 10 there is disclosed the blank which has the central portion 35 flanked by forked portions the arms H, H', and J, J' at opposite ends of which have the intervening slits 39 to facilitate the bending of these parts. In Figure 10 15 the parts of the blank shown in Figure 10 have been shaped to provide a boxing having the rear wall 38, the side walls 38', 40', the bottom wall 39' and the base portion 41. In the boxing the end of a hollow post may be 20 clamped in the manner already described, while the base portion 41 is designed to be secured to any support desired. In Figure 12 the portions of the blank of Figure 10 has been shaped to provide the elongated flat 25 member consisting of the parts 35, and H and J, to which is joined the angularly bent channel-shaped bearing or bracket consisting of the upper part 35', and the lateral walls H', and J' respectively. It is also designed to 30 provide the form of bracket shown in Figure 13 where each end has the stub 42, the inclining ledge 43, and the main length of body portion of the bracket, the usual diagonal slots 12a being shown terminating in the base holes 11a in a manner already described.

In Figure 14 there is disclosed a modification of the diagonal slot of my tubular post. Here a row of diagonal slots is provided consisting of the main hole 12c with which communicates the upwardly inclining notch 12a, there being also the laterally extending offset notch 12d arranged at right angles to the axis of the post 10. This notch extension 12d provides a rectilinearly disposed seat for the 40 terminal of whatever rod or stay is introduced therein.

One practical use, to which my invention can be put, is illustrated in Figures 5 and 7 where it is proposed to convert a window shade into an awning. Use is made of vertical columns formed by screwing the threaded stems 21' of upper hollow posts into the threaded bushings of lower posts, the stems first passing thru any of the holes M of the 45 horizontal arm 20 of the angle-iron bracket (whose vertical base portion is designated, this bushing being secured to the wall of support) 21 secured to the wall or support and the rightangular shelf 20 therein after 50 which it may be screwed home in the bushing of the lower post, so the effect is to clamp the adjacent ends of two vertically alining posts upon opposite sides of the shelf of the bracket. This having been done, and the posts being 55 provided in a manner already explained with the diagonal slots or rows thereof, a shade roller 17 is taken and the rounded and polygonal pintles thereof, designated respectively 18 and 19 are separately positioned, the 60 rounded pindle being inserted in the round

hole directly and the polygonal pindle being let into a diagonal slot and pushed downwardly so as to be frictionally seated in the base holes thereof. This positions the shade roller properly, yet allows the rounded pindle 70 to turn in its hole. In the lower transverse portion of the shade is located the fabric sleeve 23 of the shade proper 16, and in this sleeve is located a tube 25 in which is loosely encased a rod 24 whose ends project beyond the sleeve and are received into diagonal openings and base holes of slots in both posts which flank this shade. This will hold the shade 16 in vertical position but so that its lower end will not rattle as when a strong 75 wind is blowing. Now by employing two of the interchangeable posts (one being shown in Figure 7) designated 23' it will be seen that the projecting ends of rods 11g fitting these posts will enter diagonal holes or slots 80 in the posts 10 that extend vertically and are secured to the framework, which will position the inner ends of these posts 23 at right angles, and now the projecting ends of the rods 24 will enter slots in the posts 23, thus 85 enabling the shade 16 to incline downwardly and outwardly of the framework as shown in Fig. 7 and producing the awning effect. I claim all variations falling within the purview of the appended claims. 90

What I desire to claim and secure by Letters Patent is:—

1. Means of providing frame supports consisting of tubular posts having longitudinally spaced apart slots disposed diagonally of the 100 length of the post and each terminating at one end in rounded holes.

2. Means of providing frame supports consisting of tubular posts, each tubular post having sets of diametrically opposite and alining holes, with diagonally disposed and inclined offset notches forming elongated continuations diametrically of said holes, the said notches of alining holes inclining in opposite directions. 105

3. Means of providing frame supports consisting of a tubular post, an internal internally-threaded bushing carried by the post at either end for the reception of threaded pins of adjacent posts, the post being formed with 110 longitudinal rows of slots, arranged in a circumferential series, the members of each row of slots consisting of a base hole and a notch-prolongation sloping therefrom at an angle, for the reception of the terminal of a stay 115 rod. 120

4. Means of providing frame supports consisting of hollow elongated members, threaded connections carried interchangeably by 125 said members for increasing the length of a member longitudinally, each member having two sets of diametrically opposite slots, each slot of the sets of slots consisting of a rounded base hole and an inclining rectilinear notch arranged centermost of the hollow member 130

leading therefrom, the edges of each notch being parallel with the axis of this member.

5. A frame-making instrumentality consisting of an interchangeable tubular post formed with an alining series of wedge-shaped slots disposed diagonal of the axis thereof, each wedge-shaped slot having a closing edge at one end disposed parallel with the longitudinal axis of the post and having at its other end an enlarged hole.

10. 6. A frame-making instrumentality consisting of an interchangeable selectively useable hollow post, the post having a set of diametrically opposite holes, another set of diametrically opposite holes arranged at right angles to the first set of holes, a bushing internally screw-threaded and having diametrically opposite holes designed to register with a diametrically opposite set of holes in a post whereby a threaded stem may be caused to project thru the holes in both post and bushing for cross-stay purposes, each hole in the post having a diagonal slot extension following the curvature of the post.

25. 7. A frame-making instrumentality consisting of an interchangeably positionable hollow post, said post having longitudinally alining rows of holes extending circumferentially thereof, the said holes alining at diametrically opposite points of the post, diagonally arranged slot extensions formed so as to communicate with the several holes, and coupling means carried internally at one end of a hollow post serving as a means of attachment in butting relation of a mated post.

40. 8. A frame-making instrumentality consisting of a pair of hollow posts arranged in opposite positions, each post having circumferentially extending series of longitudinally arranged rows of holes, with diagonal notch extensions communicating with said holes, and a stay rod designed to connect said posts at an angle thereto and having its ends received into the diagonal extensions of both posts and let down to rest into the communicating holes thereof.

50. 9. A means of support-making consisting of a series of interchangeably positionable hollow posts, certain of the posts being arranged in vertical formation, each hollow post having a longitudinally separated alining series of slots, each slot consisting of a lower hole and an elongated diagonally disposed notch, internally-threaded bushings carried internally at the ends of certain posts, screw-shanks carried at the ends of other posts designed to screw into the bushings to continue the length of the hollow post, and angularly-arranged hollow posts having rods 60. projecting internally and having projecting terminals received initially in the diagonal notches of slots in the vertical posts and resting ultimately in the holes of said slots to provide cross-stays.

65. 10. A support-frame making unit consist-

ing of a flat metal sheet formed with a plurality of longitudinally alining rows of slots, the slots consisting each of a hole with a diagonally extending notch leading therefrom, the inclinations of the diagonal notches of the slots of the respective rows of slots varying angularly, the flat metal sheet designed to be shaped into angular or circular hollow formation to cause the rows of holes therein to aline.

70. 11. A support-frame making unit consisting of a flat sheet formed with four longitudinally extending rows of slots, each slot consisting of a base hole with an inclined notch leading angularly therefrom, the holes of said rows of slots being arranged in staggered relation, the inclined notches of the slots of the several rows of slots alternately sloping in opposite directions, said sheet designed to be shaped into a hollow post.

75. 12. A supporting column for constructions consisting of a hollow member having a pair of alining diametrically oppositely arranged holes, each hole having an angularly sloping notch extending rectilinearly therefrom, to permit a stay rod to have a terminal thereof introduced thru the angular notch of a slot and pushed downwardly therein to rest firmly in the hole thereof.

80. 13. A supporting column for construction work consisting of a hollow member having a bushing snugly secured therein at one end, the bushing having internal threads and diametrically opposite holes, the hollow member having longitudinally spaced apart diametrically opposed sets of holes, any pair of which may register with the diametrically opposite holes of the bushing, each hole of the hollow member having an angularly disposed diagonally extending longitudinally arranged notch extension.

85. 14. A bracket for supporting a shade roller consisting of a pair of hollow posts each post having a row of slots, each slot consisting of a hole and an inclined angular notch communicating therewith, the pintles of the shade roller being introduced into the angular notches and ultimately resting in said holes, and means carried by said posts and engaging the lower end of the shade of the roller for supporting the shade in angular projecting position.

90. 15. In combination, a frame, a pair of brackets secured upon the frame at opposite sides thereof, each bracket consisting of a vertical base and a rightangular shelf, the shelf of each bracket having a hole, a pair of tubular posts having at their upper ends internally threaded bores registering with the bracket hole, means engaging the lower end of the post to secure the same in vertical position, a second pair of hollow posts, inserts secured into the lower ends of the second pair of posts including threaded stems, the threaded stems being caused to project thru

the holes of the shelves so as to screw home into the threaded bores of the posts to position and to clamp the upper posts in vertical alinement with the lower posts, on opposite 5 sides of the bracket shelves respectively, each post having circumferential series of diagonal slots with hole-shaped relatively wider base portions.

16. In a device as described, in combination 10 a frame consisting of oppositely arranged parts, a pair of vertical hollow posts secured in front of said oppositely-arranged parts, each post having vertically alining rows of diagonally inclined slots, a shade 15 roller having its pintles received in said downwardly inclined slots of both posts, a sleeve disposed in the lowermost end of the shade of the shade roller, a rod projecting thru said sleeve with its ends projecting 20 therefrom and extending towards said posts, a pair of hollow posts having each a terminal received in fixed relation within one of the inclined slots whereby these posts extend forwardly at right angles to the other posts, the 25 last-named posts also being formed with inclined slots receiving the projecting ends of the rod of the shade whereby the shade may be positioned at a downward and forward inclination from its roller.

30 In witness whereof he has hereunder set his hand this 17th day of December, 1929.

THOMAS E. MARKLEY.
